UNITED STATES PATENT OFFICE.

MARY E. THOMPSON, OF NEW YORK, N. Y.

HAIR HEAD-DRESS OR WAVE.

SPECIFICATION forming part of Letters Patent No. 276,306, dated April 24, 1883.

Application filed October 17, 1882. (No model.)

To all whom it may concern:

Be it known that I, MARY E. THOMPSON, a citizen of the United States, residing at New York, in the county of New York and State of New York, have invented a new and useful Improvement in Ladies' Head-Dresses or Waves, not heretofore known; and I do hereby declare the following to be a full, exact, and clear description of the same, reference being had to the accompanying drawings as a part of this my specification.

Figure 1 is a perspective view of the under side or back of said head-dress or wave. Fig. 2 is an upper or top view of the same. Fig. 3 is a view of the frame or spring A without any hair attachment thereto.

Like letters indicate like parts wherever they occur.

My invention relates to an improved construction of ladies' head-dresses or waves, and is to be worn upon the forward or fore part of the head, either as a protection to the natural hair, or for the concealment of real or fancied defects in the hair of the wearer, or to obtain some effect to the eye not capable of being produced by any arrangement of the natural hair of the wearer, yet at the same time to be so natural in its appearance as to escape detection, or excite any suspicion of an artificial addition to the natural hair of the wearer.

I am aware that head-dresses or waves have been designed or patented designed to show the natural parting of the wearer without foundation-lace parting, but believe that all attempts have been failures, and none of them have had in their construction a spring of my description in any respect.

In all ladies' head-dresses or waves as now constructed the great difficulty in making them appear natural and inartificial has been so arranging them as to represent the natural parting of the hair. The most successful device heretofore employed for this purpose is to make the parting upon white lace, which is designed not to show upon the scalp of the wearer, the principal example of which is found in my Letters Patent of February 6, 1877, No. 187,198; but I have found by experience that this cannot be relied upon with any certainty, as the presence of white lace can be discovered upon close scrutiny, or upon its becoming soiled or

displaced upon either side of the natural parting in actual use by the wearer.

I will now proceed to describe my invention, so that others skilled in the art to which it applies may apply the same.

In the drawings, A represents a continuous spring in a wave open at the forward ends, and should be placed with the center space between the jaws of the spring directly over the natural parting of the hair. B represents the open space between the jaws of the spring. The head-dress or wave may be made of either natural or artificial hair. The wave or head-dress is secured or fastened to the spring upon the usual foundation of lace or hair-work, and may be of any desirable shape, size, or formation, and is attached to the spring in the usual way. No lace or foundation of any kind is between the arms or jaws of the spring A; but the hair is so arranged or extended over or between the jaws or arms of the spring that it nearly covers the open space between the arms of the spring, and in such manner that the scalp or natural parting-line of the wearer is shown, and thus doing away with any artificial parting and making or disclosing the natural and truthful parting of the hair of the wearer, and obviates any artificial parting-lace or foundation of any kind between the jaws of the spring. The spring may be made of any thin metallic or vegetable substance, either metal, rubber, or celluloid; but should be of sufficient elasticity to retain its position when placed upon the head, and of such thinness as not to be noticeable when the wave is placed upon the head. To make it more secure and render it less liable to injury when placing it upon the head, a hair or fine thread of the same color with the hair of the wave may be stretched across the open ends of the spring upon which the wave or head-dress is formed or attached. I preferably make this spring with slightly-flaring sides, as shown in the drawings; but I do not wish to confine myself to the exact form shown, as it may be made in several different forms to accomplish substantially the same result—i. e., the horse-shoe form, or perfectly parallel sides. The spring also should be made to conform to the shape of the head of the wearer, or of such material as to conform itself to the shape of the

head when so bent. These are matters of detail.

The principal invention or discovery which I here claim is the doing away with the foundation or lace between the jaws of the spring and the substitution or utilization of the natural parting of the hair or scalp of the wearer therefor, as shown in the drawings.

In actual use the hair of the wave covers and hides completely the spring, and extends each side of the arms of the spring so as to blend with the natural hair of the wearer, when desired, and discloses only the natural parting. This mode of construction is much cheaper in manufacture and more effective, avoids the difficult and tedious labor of knotting the hair and lace to form the artificial parting, is much

more durable, and does away entirely with any false or artificial appearance.

Having thus described my invention, what I claim, and desire to secure by Letters Patent, is—

As a new article of manufacture, a lady's head-dress or wave composed of natural or artificial hair, in connection with the spring A, and so arranged, in combination and connection with the spring A, as to form the open space B, and thus utilize and exhibit the natural parting of the hair of the wearer, substantially as shown and described.

MARY E. THOMPSON.
